[57] CLAIM

The ornamental design for a key ring pill container, as shown and described.

DESCRIPTION

FIG. 1 is a front elevational view of the key ring pill container showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

In FIG. 7, the broken line showing of a prescription pill bottle is for illustrative purposes only and forms no part of the claimed design. FIG. 7 is an exploded front elevational view.
